UNITED STATES PATENT OFFICE

ATTILIO FRANCO, OF MILAN, ITALY

HEATING APPARATUS FOR RAILWAY CARS

Application filed February 10, 1925, Serial No. 8,218, and in Italy February 11, 1924.

The present invention has for its subject matter a novel system of heating railway cars by means of hot water. The term "railway cars" as used throughout the specification and claims includes freight cars as well as passenger coaches.

In the accompanying drawings some forms of the invention are illustrated by way of example.

Fig. 1 gives the general diagram of the novel heating system.

Figs. 2 and 3 respectively are a longitudinal elevation and a plan showing the heating system as applied, by way of example, to a passenger coach.

Fig. 4 shows the heating plant installed on a locomotive having the fire-box at its front end.

Figs. 5 and 6 show in longitudinal elevation and plan respectively the arrangement according to the invention as applied to a passenger coach having doors only at the ends of the coach.

Figs. 7 and 8 show in longitudinal elevation and plan respectively the arrangement according to the invention as applied to a passenger coach in which the doors are distributed along the whole length of the coach.

Fig. 9 is a horizontal section of the couplings on the ends of each car when water is used for heating or refrigerating the train.

Fig. 10 is a horizontal section of the couplings on the ends of each car when steam is used for heating the train.

Referring to Figs. 1 to 4, 1 is a tubular pressure boiler for heating the water; 2 and 3 are respectively the water inlet and the water outlet pipes thereof; 4 and 5 are respectively the inlet and the outlet pipes for the combustion gases or exhaust steam that are used to heat the water, the hot gases or exhaust steam flowing outside and the water flowing inside of the tubes provided in the boiler 1.

6 is a pump driven in any convenient manner, drawing the water through the suction pipe 7 from the atmospheric pressure tank 8 and forcing it through the delivery pipe 9 into the inlet pipe 2, boiler 1 and outlet pipe 3.

From the pipe 3 a branch 3' leads to a cock 10, and another branch 3'' to a cock 11. A flexible hose 12 connects the cock 10, which is mounted on the locomotive, to the main pipe line 13 running along the train.

In the branch 3'' leading to the cock 11 is fitted an injector 14 conveying the fluid in the direction indicated by the arrow —a— towards the main pipe line 13.

The cock 11 is further connected to a pipe 15, through which live steam can be supplied by the locomotive's boiler to the injector 14 when the cock 11 is open.

Between the boiler 1 and the injector 14, a cock 16 is provided in the pipe 3' in order to control the flow of the water supplied through boiler 1, pipe 2, pump 6 by tank 8.

A pipe 17 branches from the pipe 3' and is connected to a cock 18; to this cock 18 is connected also a pipe 19, through which the water from the locomotive's boiler can be directly conveyed to the cock 18 and pipe 17.

On the pipe 17 a stop valve 20 is fitted, controlling the boiler water supply to the pipe 17.

Between the boiler 1 and the pump 6 a cock 21 is provided in the pump delivery pipe 2 for the purpose of controlling the water flow from the pump 6 into a pipe 22, one end of which is connected to a cock 23 and therewith to a flexible hose 24. In this manner the pipe 22 provided on the locomotive is connected, through the flexible hose 24, to the return end of the main pipe line 13 heating the whole train.

The pipe 22 therefore receives the return water from the main pipe line 13 and, if the cock 21 is so set as to close the communication between the pipe 22 and the pipe 2, this water will go to a cock 25. The cock 25 is connected on one side to a radiator 26 (serving to cool down the water) and on the other side, through a pipe 27, to the atmospheric pressure tank 8. This tank 95 and the radiator 26 are interconnected by a pipe 28.

The cock 25 may connect the pipe 22 to the radiator 26 and disconnect it from the pipe 27 and tank 8, or conversely it may

connect the pipe 22 to the pipe 27 and tank 8 and disconnect it from the radiator 26.

A switch cock 29 serves to reverse the direction of flow in the suction pipe 7 and delivery pipe 9 of the pump, or in other words to make 7 work as delivery pipe and 9 as suction pipe.

By operating the cock 29 the pipes 7 and 9 can be so interconnected that, without reversing the movement of the pump, the pipe 7 draws the water through the duct 30 (shown in dotted lines) from the pipe 2 instead of forcing it thereinto, and the pipe 9 forces the water, through the duct 31 (shown in dotted lines), into the tank 8, instead of drawing it therefrom when it is desired to empty the main pipe line by means of the pump 6 and to convey its water back into the tank 8.

20 On the contrary, when the train is to be heated, the left halves of the ducts 30, 31 form an intermediate portion of the suction pipe 7, while the right halves of said ducts form a portion of the delivery pipe 9.

25 At a convenient point a cock 32 is fitted on the pipe 2; to this cock a pipe 33 is connected, through which steam from the locomotive boiler may be supplied.

The main pipe line 13 is divided essentially into two thermal sections.

The first section starts from the cock 10 and extends to a joint 35; the second section starts from the cock 23 and extends to a joint 34; a pipe connection 36 connects the 35 two sections.

The thermal section extending from 10 to 35 is the outgoing branch, the thermal section extending from 23 to 34 is the ingoing or return branch.

40 Each of the two sections may be used at will as outgoing or as return branch.

In the path of the main pipe line 13 are several spaces to be heated indicated in Fig. 1 by the rectangles 37, 38, 39, 40; 41, 42, 45, 44; and 45, 46, 47, 48.

Each rectangle contains a length of the outgoing and an equal length of the return thermal branch, and the sum of the surfaces of the said two pipe lengths constitutes a constant of the heating plant in the sense that the total heat given off, for instance, by the two lengths (49—50) and (51—52), is always constant, whatever may be their position and their distance from the 55 water boiler 1.

Equal heating of the spaces A and B, see Fig. 1, will result from an average water temperature of 100° C. in the length (61—62) of the outgoing branch in the space 60 A; 84° C. in the length (63—64) of the outgoing branch in the space B; 80° C. in the length (65—66) of the return branch in the space B; and in consequence approximately 64° C. in the length (67—68) of the return branch in the space A.

The amount of heat given off to the space A is proportional to the radiating surface and to the average temperature

$$\frac{100+64}{2}=82^{\circ}\text{C.}$$

70

of the said surface.

The amount of heat given off to the space B is proportional to the radiating surface and to the average temperature

75

$$\frac{84+80}{2}=82^{\circ}\text{C.}$$

of the said surface. Since the radiating surfaces are equal in the two spaces, the 80 amounts of heat given off to the two spaces will also be equal.

Each compartment, in addition to the horizontal pipes above described, contains a system of vertical pipes. As shown in Fig. 1 vertical pipes 118 are connected to the outgoing branch and pipes 120 are connected to the return branch. The heating surface of the vertical pipes 118 is always equal to the heating surface of pipes 120 within each compartment so that equal heating of all compartments as previously stated is not disturbed.

The vertical pipes 118 within one car are all connected together at the tops thereof by a slightly inclined longitudinal pipe 122 which is provided with a cock 123 at the highest point. Also the pipes 120 within one car are all connected at the tops thereof by a slightly inclined longitudinal pipe 124 which is provided with a cock 125 at the highest point thereof.

The heating pipes 118 length, vertical pipe and the slightly inclined longitudinal pipe 122 connected to the outgoing branch 105 are designed and selected so that the combined heating surface thereof is equal to the combined heating surface of the pipe length, pipes 120 and the slightly inclined longitudinal pipe 124 connected to the return 110 branch.

The main pipe line 13 may be subdivided into any desired number of lengths by providing for each length four special three-way cocks described hereinafter.

The pipe line lengths contained in the space 37, 40, 48, 47 have at the ends thereof the 3-way cocks 69, 70, 71 and 72; branches 73 and 76 of the 3-way cocks 69 and 70 respectively lead to by-pass pipe 77 and branches 74 and 75 of 3-way cocks 72 and 71 respectively lead to by-pass pipe 78.

By operating the said 3-way cocks the water can be taken from the main pipe line 13 and conveyed through the pipes 77 and 78. It is possible thereby to cut off the pipe line portion in the space 37, 40, 48, 47 without diminishing or stopping the circulation of hot water in the remainder of the pipe line 13.

115

120

125

130

The pump 6 shown in Fig. 1, not only circulates the water through the heating plant, but also serves to regulate the heat delivered to the radiators, since the heat delivered thereto is proportional to said pump speed.

Steam is conducted from the locomotive boiler through the pipe 15 and cock 11 to heat the water in the system whenever it cannot be adequately heated in the boiler. 10 The object of the injector 14 is to assist in increasing the velocity of the water circulation in the main pipe line 13.

Figs. 2 and 3 illustrate in longitudinal elevation, and plan respectively the arrangement of the main pipe line as applied to a railway passenger coach.

The outgoing branches 84 and the water return branches 85 are positioned in the passenger coach as shown in Fig. 3.

20 Each compartment 86, 87, 88, 89, 90, 91 contains the two outgoing and return thermal lengths having the necessary surface to form the heating constant.

25 The special three-way cocks 92, 93, 94, 95 serve to control the heating of each car or coach. The auxiliary cocks 96, 97, 98, 99, are part of the 3-way cocks 92, 93, 94, 95 respectively and serve to control the circulation of hot water in by-pass pipes 100.

30 Fig. 4 shows the heating plant installed on a locomotive, the fire-box of which is arranged at the front end of the locomotive.

In this figure, 107 is the water circulating pump, 108 the injector, 109 the switch cock 35 fitted on the pump suction and delivery pipes, 110 the atmospheric pressure water tank, 111 the live steam supply pipe, 112 the radiator for cooling down the water, 113 the suction piping through which water is drawn from the tank 110 by the pump 107, 40 114 is the water boiler, 115 is the free flow pipe through which the return water is delivered back into the tank 110.

45 It should be noted that with steam locomotives the hot water intake for the main heating pipe line might be placed directly on the locomotive's boiler in accordance with what has been set out in reference to the general diagram given in Fig. 1 through 50 pipe 19, cock 18, stop valve 20 and piping 17.

According to the modifications shown in Figs. 5 to 10 additional pipes and cocks are provided in order to make it practicable to discharge the water from each vehicle 55 without disconnecting the hose pipes that connect the end cocks of one car to those of the adjacent car. Further objects of said modifications are: to avoid the noxious effect of occasional water hammering, to prevent the formation of air pockets and consequent restriction of the passage area of the heating or refrigerating piping, and to permit the use at will of either steam or 60 hot water for heating, and water or re-

frigerating solutions (brine for instance) for refrigerating freight cars.

With reference to Figs. 5 and 6, 116 is the outgoing and 117 the return thermal branch; 118 are the vertical pipes joining the outgoing branch 116 at 119, at the highest points of said branch; 120 are the similar vertical pipes joining the branch 117 at the latter's highest points 121; 122 is the pipe extending through the car and 75 serving to connect the tops of the uprights 118 with each other; 123 is the cock provided at the highest point of the pipe 122; 124 is the pipe extending through the car and serving to connect the tops of the uprights 120 with each other; 125 is the cock provided at the highest point of pipe 124.

Pipes 126 serve to drain the water from the branch 116 into the pipe 127. The pipe 127 is arranged outside of and below the car frame, a cock 128 being provided at its lowest point. Pipes 129 serve to drain the water from the branch 117 into the pipe 130 which is also arranged outside of and below the car frame, 131 being the cock provided 90 at the lowest point.

132, 133, 134 and 135 are the four pairs of main and auxiliary cocks, see Fig. 6, mentioned above with reference to Figs. 2 and 3. By suitably operating these cocks 95 the water can be switched from the main's branches 116 and 117 into the by-pass pipe 136 arranged outside of the car. At the lowest point of this pipe a set is provided consisting of a steam separator 137, a steam 100 trap 138, and a cock 139 interposed between 137 and 138. 140 are the four coach door openings provided at the two ends of the passenger coach under consideration.

In Figs. 7 and 8, 141 are the door openings provided along the sides of a passenger coach. Owing to the position of the doors, the lengths 142 and 143 of the outgoing and return branches of the heating main are arranged partly in the compartments and 110 partly outside of said compartments in a different manner from that indicated for the corresponding pipe lengths 116 and 117 in Figs. 5 and 6, whereas the arrangement and position of the remaining pipes and 115 cocks are the same as in said Figs. 5 and 6.

In Fig. 9 the positions of the passages 144, 145, 146 and 147 of the main cock plugs and the passages 148, 149, 150 and 151 of the auxiliary cock plugs in each car show 120 that the water entering in the direction of the arrow *a* is compelled to flow through the main length 152; wherefrom it issues in the direction of the arrow *b* through the passage 145; on its return the 125 water flows in the direction of the arrow *c* through the passage 146 into the length 153 of the return branch and, finally, travelling in the direction of the arrow *d*, flows through the cock passage 147. 130

The passages 148, 149, 150 and 151 of the auxiliary cocks are shown closed; accordingly no water can pass from the lengths 152 and 153 through the ducts 154, 155, 156 and 157 into the pipe 158 arranged outside of and below the car.

The position indicated in Fig. 12 for the cock-plug passages is the normal one when water is used for heating or for refrigerating the cars. Fig. 10 shows the position of the main cock plug passages 165, 166, 167, 168 and of the auxiliary cock plug passages 169, 170, 171, 172, when steam is used to heat the train.

Assuming the steam to enter in the direction of the arrow —e—, the position of the main passages 165, 166, 167 and 168 compels the steam in all cars to pass through the underlying pipes 176. Since, however, the auxiliary cock-plug passages 169, 170, 171 and 172 are then open, a portion of the steam flowing through the pipe 176 will pass through the ducts 177 and 178 into the thermal branch 179 and through the ducts 180 and 181 into the thermal branch 182 and heat the vehicle. The condensate forming in the thermal branches 179 and 182 will be discharged (as shown in Fig. 5) through the passages 126 and 129, when the cocks 128, 131 are open; while the condensate forming in the pipe 176 will be discharged through the steam trap 138 connected to the steam separator 137 as shown also in Fig. 5.

While I have used the term "railway car" in the claims, I wish it to be understood that the invention as defined may be applied equally well to each compartment of a car and that such a construction comes within the scope of my invention.

Having now particularly described and ascertained the nature of my invention and in what manner the same is to be performed, I declare that what I claim is:

1. In a railway car, heating apparatus for said car, comprising, in combination, a main pipe comprising an outgoing branch and a return branch, a pair of 3-way cocks connected in said outgoing branch, a heating pipe length in said car and a by-pass pipe connected in parallel between said cocks, a second pair of 3-way cocks connected in said return branch, a second heating pipe length in said car and a second by-pass pipe connected in parallel between said second pair of cocks, said first heating pipe length and said second heating pipe length having equal heating surfaces.

2. In a railway car having a roof, heating apparatus for said car, comprising, in combination, a main pipe comprising an outgoing branch and a return branch, a pair of 3-way cocks connected in said outgoing branch, a heating pipe length in said car and a by-pass pipe connected in parallel be-

tween said cocks, a plurality of vertical pipes connected at intervals to said heating pipe length, a longitudinal pipe near said roof, the upper ends of said vertical pipes being connected to said longitudinal pipe, a second pair of three way cocks connected in said return branch, a second heating pipe length in said car and a second by-pass pipe connected in parallel between said second pair of cocks, a second plurality of vertical pipes connected at intervals to said second heating pipe length, a second longitudinal pipe near said roof, the upper ends of said second plurality of vertical pipes being connected to said second longitudinal pipe, valves positioned on the ends of said longitudinal pipes, the combined heating surfaces of said first heating pipe length, said first vertical pipes and said first longitudinal pipe being equal to the combined heating surfaces of said second heating pipe length, said second plurality of vertical pipes and said second longitudinal pipe.

Signed at Milan, Italy, this 16th day of January, 1925.

ATTILIO FRANCO.
